Inventor

UNITED STATES PATENT OFFICE.

JAMES HUGH HORAH, OF SALISBURY, NORTH CAROLINA.

BICYCLE.

SPECIFICATION forming part of Letters Patent No. 451,972, dated May 12, 1891.

Application filed September 6, 1890. Serial No. 364,127. (No model.)

To all whom it may concern:

Be it known that I, JAMES HUGH HORAH, a citizen of the United States, residing at Salisbury, in the county of Rowan and State of North Carolina, have invented certain new and useful Improvements in Bicycles; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a new and improved brace, leg, or lateral support for bicycles, and is designed to retain the machine, without or with a rider, in an erect position when at rest.

The invention consists in the construction 20 and arrangement of the several parts of a support or brace, of which the following is a description, reference being had to the accompanying drawings, forming a part of this specification, in which similar letters of reference 25 indicate corresponding parts in all the figures.

Although this invention can be applied to other styles of bicycles, it is shown here in connection with that class known as the "Safety," which consists of two wheels of nearly 30 or quite equal size joined by a spine or backbone.

Figure 1 is a three-quarter view of a "Safety" machine, showing the brace when not in use. Fig. 2 is a similar view of the same, 35 showing the brace when in position and in use.

The brace or support consists of a rod *b b*, joined to the front fork of the machine by a folding lever *d* and to the handle-bar of the 40 machine by a lever *h*. The rod *b b* has a small wheel *a* at its lower end. The folding lever *d* is hinged to the fork of the machine by an adjustable clamp *e* and to the rod *b b* by an adjustable clamp or block *c*, which can be 45 placed at any necessary part of the rod *b b*. The folding lever *d* extends past the rod *b b*, and at the outer end *o* is fastened a spring *f*, which spring is joined to the rod *b b* below the clamp *c* by the eye *p*. At its upper end 50 the rod *b b* is joined by a hinge *g* to the lever *h*. This lever *h* is hinged to the handle-bar

of the machine by the adjustable clamp *i*, and its motion in a perpendicular plane is controlled by said hinge *g* and by the segment *k*, which has two holes *l* and *l'*, and which is 55 adjustably clamped to the handle-bar of the machine at a point between the clamp *i* and the outer end of the handle-bar. The position of the lever *h* is regulated by the spring-latch *n*, attached to said lever *h*, and by the 60 pin *m*, placed at the inner end and forming part of said spring-latch *n* in such a position that it engages the holes *l* and *l'*.

When the brace is in use, as in Fig. 2, the pin *m* is held by the spring-latch *n* in the hole 65 *l'*. When the brace is not in use, as in Fig. 1, the pin *m* is similarly held in the hole *l*.

The object of the spring *f* is to overcome the dead-center created by the alignment of the folding lever *d* and the rod *b b* when the 70 brace is not in use. Without this spring the downward pressure exerted at the point *g* by the lever *h* would fail to lower the brace from its inactive to its active position on account of the dead-center created by the aforesaid 75 alignment. The spring *f*, being in tension when the brace is not in use, pulls the point *o* of the folding lever *d* toward the eye *p* on the brace-rod, and when the lever *h* is moved upward overcomes this dead-center and as- 80 sists in bringing the brace into its active position.

A hooked arm or catch *s* is pivoted upon a spring-washer to the front side of the rod *b b* just above the small wheel *a*. When not in 85 use, this arm lies parallel to and against the rod *b b*, as shown in Fig. 1. When necessary to use the catch, it is revolved upon its pivot downward and in an outward direction from the front wheel of the bicycle until it engages 90 and locks the small wheel *a* and prevents it from turning. This catch locks the small wheel and prevents it from rolling around and turning the front wheel of the bicycle upon its axis, and thereby destroying the sup- 95 port afforded by the brace. This will not happen when the rider is seated upon the machine or when the machine is left standing upon a surface which is sufficiently rough to prevent the wheel *a* from rolling.

Instead of a solid rod, the brace *b b* can be made adjustable in length, as in Fig. 1, by

means of a rod operating in a tube and held in position by a set-screw *q*. The brace can be made equally well of a solid rod of proper length for the particular style of machine, 5 and I do not confine myself to the tube and adjustable rod.

For the purpose of adding strength and stability to the brace a guide *r* is clamped to the handle-bar support of the machine and 10 the rod *b b* is passed through said guide. This guide can be dispensed with, when desired, and is intended to relieve any unusual or extraordinary strain upon the other parts of the brace, and more particularly upon the segment *k*. 15

When the rider desires to use the brace or support, he presses the spring-latch *n*, thus withdrawing the pin *m* from the hole *l*, and raises the lever *n* to the position shown in 20 Fig. 2. This, together with the action of the folding lever *d* and the spring *f*, brings the rod *b b* downward and outward laterally from the machine until the wheel *a* touches the ground. The spring-latch is then released and the pin 25 *m* goes into the hole *l'*. The brace is then held firmly in position, and the rider can stop the machine and remain seated thereon, or can leave it standing in an erect position without other support than that afforded by the brace. 30 When the brace is no longer needed, the lever *h* can be lowered and the brace restored to its inactive position.

Having thus described my invention, what I claim as new, and desire to secure by Letters 35 Patent, is—

1. In a bicycle, the combination, with the fork and handle-bar thereof, of a brace or lateral support for said bicycle connected by a lever with the handle-bar of said bicycle and with the fork thereof by means of clamps 40 and a folding lever, substantially as set forth.

2. In a bicycle, the combination, with the handle-bar thereof, of a brace or lateral support connected with said handle-bar by clamps and by a lever regulated by a spring-latch and 45 a segment, substantially as set forth.

3. In a bicycle having a brace or lateral support, the combination, with a folding lever connecting said brace and said bicycle and extended past said brace, of a spring connecting the extended end of said folding lever with said brace or lateral support, substantially as set forth. 5c

4. In a bicycle having a brace or lateral support, the combination, with a wheel on the 55 lower end of said brace or lateral support, of a catch pivoted on said brace and adapted to lock said wheel, substantially as set forth.

5. In a bicycle, the combination, with a brace or lateral support therefor, of a guide for said 60 brace or lateral support clamped upon the handle-bar support of said bicycle, substantially as set forth.

In testimony whereof I affix my signature in presence of two witnesses.

JAMES HUGH HORAH.
